LIGHT SIGNAL

Oscar S. Field, Rochester, N. Y., assignor to
General Railway Signal Company, Rochester,
N. Y.

Application September 23, 1929, Serial No. 394,455

2 Claims. (Cl. 177—327)

This invention relates to signals particularly adapted for railway use, and has more specific reference to a direct current railway signal giving a plurality of indications.

It has been proposed to provide color light signals having a plurality of color screens which may be passed between the lens of the signal and its internal light source, such for example, as set forth in my pending application Ser. No. 128,437 filed August 10, 1926, now patent No. 1,835,150, to prevent phantom or false indications due to the reflection of external light sources.

Among the objects of this invention is to provide a unit type light signal giving a plurality of indications by means of movable color screens, as above mentioned, with these color screens operably controlled by direct current polar-neutral tractive type magnets.

Other objects, purposes and characteristic features of the present invention will be in part obvious from the accompanying drawings and in part pointed out as the description of the invention progresses.

In describing the invention in detail, reference will be made to the accompanying drawings, in which like reference characters refer to like parts in the several figures, and in which:—

Fig. 1 is a rear elevational view of a signal mechanism embodying the present invention with certain parts removed and with other parts shown in section;

Fig. 2 is a right hand side elevational view of the embodiment with portions shown in section;

Fig. 3 is a left hand side elevational view of the embodiment with portions shown in section;

Fig. 4 is a sectional plan view, taken on line 4—4 of Fig. 2;

Fig. 5 is a diagrammatic view showing typical circuits in which the present invention may be used.

The color light signal, shown as one embodiment of the present invention, includes four distinctive groups of apparatus, namely, the devices used in the optical arrangement, the direct current polar-neutral tractive type motor mechanism, the operating mechanism, and the circuit controlling contacts. These various devices are interrelated and cooperate in such a manner that the signal gives a plurality of indications of varying restrictiveness according to the presence and polarity of the energizing direct current.

Referring now to the drawings, color screens

or roundels R, Y and G are mounted upon a movable member 5 (see Fig. 1), which passes through a focal point F of an elliptical reflector 6 (see Fig. 2). An incandescent bulb 7 is held in position at the internal conjugate focus of the reflector 6 by means of a suitable adjustable socket arrangement mounted upon a casing 8. The function and arrangement of the light projecting optical devices is more fully described in my above referred to application Ser. No. 128,437, filed August 10, 1926.

It is considered sufficient for explaining the present invention to state, that the light rays from the incandescent bulb 7 and the reflector 6 meet at the external conjugate focal point F, which is at the center of the color screen then between the lamp unit and the lens unit (not shown). The light rays then spread from this focal point F and pass through a conical shield 9 to the lens unit.

The casing 8 of the lamp unit is suitably secured to a casing 10 which in turn is suitably secured to the main frame member 3 of the signal unit.

This frame member 3 is of non-magnetic material and serves as a mounting for the motor mechanism. Two cores 11 and 12 are mounted on the frame member 3 and have pole pieces 13 and 14 suitably connected to the frame member 3 (see Fig. 1). On the core members 11 and 12 are placed coils 15 and 16 having lead wires (not shown) connected to a terminal block 17 mounted on a back strap 18 which is clamped to the cores 11 and 12 to furnish a good magnetic path therebetween.

Cooperating with the pole pieces 13 and 14 is a neutral armature 20 (see Fig. 3) mounted on suitable trunnions which turn in bearings 21 supported by a bracket 22 adjustable in respect to the frame member 3. On the neutral armature 20 are residual pins 23 which serve to determine the minimum air gap between the neutral armature 20 and its coacting pole pieces 13 and 14, thus eliminating the possibility of the neutral armature 20 becoming stuck in an energized position due to residual magnetism within the coacting members.

With reference to Fig. 2 of the drawings, the polar magnetic structure includes a support bracket 25 of magnetic material connected to the main frame member 3 by screws 26. This support bracket 25 is angular in form, with a horizontal portion 25^a and a vertical portion 25^b.

The horizontal portion 25^a has two upstanding hollow bosses which receive cores 27 and 28 upon

20

25

30

35

40

45

50

55

which are mounted coils 29 and 30. These core pieces 27 and 28 are magnetically inter-connected by the same back straps 18 which magnetically interconnect the core members 11 and 12.

5 The vertical portion 25^b of the support bracket has attached thereto, by screws 31, a yoke 32 of non-magnetic material, in which yoke is adjustably mounted a spindle 33 on trunnions 34. A polar armature 40 is mounted on the spindle 10 33, which armature is right angular in shape to correspond to the shape of the support bracket 25. This polar armature 40 has a vertical portion which passes around the yoke 32 in a manner to be adjustably mounted upon the spindle 33. This 15 arrangement permits the polar armature 40 to pivotally swing between the pole pieces 13 and 14 with the minimum air gap determined by residual pins 53.

20 The cores 27 and 28, with their respective coils 29 and 30, may be conveniently termed in a collective manner, the polarizing electro-magnet, as the coils 29 and 30 are so connected that the corresponding ends of the cores 27 and 28 have the same polarity, as for example, the upper ends 25 north and the lower ends south as indicated by the reference characters N and S respectively (see Fig. 2), thus causing the polar armature 40 to always be of one polarity.

25 Similarly, the cores 11 and 12, with their respective coils 15 and 16, may be termed in a collective manner, the operating electro-magnet, as the coils 15 and 16 are so connected that the pole pieces 13 and 14 are of opposite polarity. This causes the flow of flux from the cores 27 and 28 30 to pass upwardly through the back straps 18, down through one or the other of the cores 11 or 12, depending on the particular direction of energization of the coils 15 and 16, through the corresponding pole pieces, to the horizontal portion 35 of the polar armature 40, and thence through the horizontal and vertical portions 25^a and 25^b of the support member 25 to the lower ends of the cores 27 and 28. It is now apparent that the polar armature 40 being of one polarity will swing 40 with its spindle 33 to have its horizontal portion in contact with one or the other of the pole pieces 13 or 14, depending upon the direction of the current flow in the coils 15 and 16 of the operating electro-magnet. Also, upon energization of 45 the operating electro-magnet, the neutral armature 20 is actuated to an energized position in the usual well known manner.

50 The above described magnetic structure is practically identical with that set forth in my pending application Ser. No. 305,408 filed September 12, 1928, now Patent No. 1,749,331, issued March 4, 1930, in which the construction and operation is set forth in detail.

55 The operating mechanism which operatively connects the motor mechanism with the color screens mounted upon the movable member 5, consists of connecting means between each of the armatures 20 and 40 respectively, and said movable member 5, in which member 5 the combined action of both armatures selects the less restrictive indications.

60 The movement of the armature 40, from its position in contact with the pole piece 13 to its other position in contact with the pole piece 14, 65 controls the selection of either the green or yellow screen G or Y respectively to be positioned at the focal point F, if the neutral armature 20 is at that time energized, at which time the movable member 5 is raised from its lowered biased position in

which the red color screen R is at the focal point F.

Attached to the spindle 33 and the vertical portion of the polar armature 40, is a lever 41 which is rigidly connected to an angularly shaped 5 connector 42 which is pivotally connected to a vertical control lever 43. This vertical control lever 43 is pivotally connected at its upper end to a rocker arm 44. A guide member 46 is pivotally connected to the frame member 3 by a tap 10 bolt 47 and is rocked on this pivot point by movement of the rocker arm 44 on its pivot point 35, which rocker arm 44 is slidably connected to the guide member 46 within a slot 46^a.

Attached to the movable member 5 is a guide 15 bolt 48 which rides within a slot 46^b within the guide member 46, in such a manner that when the movable member 5 is in its shown normal position, the center line of the guide bolt 48 coincides with the center line of the pivot point provided by the tap bolt 47. With the movable member 5 in its shown normal position, it rests upon a bracket 49 which is secured to the frame member 3 by a bolt 50.

20 The neutral armature 20 has connected to it 25 a lever arm 52 which has an adjustable spring bracket 51 adjustably tensioned by a bolt 54. Pivotally to this bracket 51 is a rod 55 which is also pivotally connected at the opposite end to a yoke 56 that is pivotally supported by bracket members 57^a and 57^b suitably attached to the frame member 3.

25 The yoke 56 is trunnioned in an adjustable bearing 58 within bracket member 57^a and an adjustable spring tensioned anchor 59 within bracket member 57^b. A spring 60 is attached at one end to the yoke 56 and at the other to the anchor 59 with the biasing tension such as to compensate for the weight of the movable member 5 and is definitely secured by a set screw 61 engaging the 40 irregular periphery of the anchor 59.

30 A supporting lever 62 is suitably trunnioned in an adjustable bearing 64 within bracket member 57^a and within adjustable bearing 65 within bracket member 57^b (see Fig. 3) and having its 45 extreme end pivotally connected to movable member 5 (see Figs. 1 and 2). This supporting lever 62 is pivotally connected with the yoke 56 by a connecting link 66 which is connected to each member respectively by pins 67 and 68.

35 Thus, it is seen that the energization of the neutral armature 20 raises the movable member 5 to an upper extreme position. At this time the center line of the guide bolt 48 is moved to such a position that the guide member 46 now has 55 a lever arm to move the guide bolt 48 either in a clockwise or a counter clockwise direction. At the same time that the neutral armature 20 is energized, the polar armature 40 is actively attracted by either the pole pieces 13 or 14 depending 60 upon the polarity applied, which results in the movement of the guide member 46 to either a right hand or left hand position, which selects either the color screen Y or the color screen G 65 respectively.

65 As a polar armature of such a mechanism is more quick to respond to the energization of its operating coils, than is a neutral armature, it is possible for the guide member 46 to assume its 70 selected position slightly before the neutral armature 20 raises the movable member 5 which permits the changing of the indication from that given by the color screen R to the indication given by the color screen Y without a passing 75

flash of the indication which might be given by the color screen G, if such were not the case.

A plurality of fingers 12, of like construction, is connected to the neutral armature 20, each finger comprising two spring mounting members 13 and 14. The member 13 carries a, movable front contact 15 of coin silver or the like, to cooperate with a fixed front contact 16 of carbon, or the like, while the member 14 carries a movable back contact 17 of coin silver, or the like, to cooperate with a fixed back contact 18 of coin silver, or the like. These contacts can be used for any desired purposes.

Fixed to the yoke 32 is another yoke 80 which supports adjustable pivot points 81 and 82 serving as mountings for a support member 83. The support member 83 is operably controlled by the polar armature 40 through a slid able pivot provided by a roller 89, which is secured to support member 83. This roller 89 engages a slot in an arm 95 which is secured to the polar armature 40. A block 84 of insulating material is suitably attached to the support member 83. This block 84 carries a movable front contact 85 of coin silver, or the like, to cooperate with a fixed front contact 86 of carbon, or the like, while a movable back contact 87 is carried to cooperate with a fixed back contact 88.

The terminal bolts and nuts for the back and front fixed contacts and for the movable contacts are suitably supported by an insulating terminal board 90 which is secured to the main frame member 3 by tap bolts 91. The operating mechanism and contacts are further inclosed by a glass housing 92 which is secured in position by thumb nuts 93 threaded on stud bolts 94.

With reference to Fig. 5, a stretch of railway track has been shown as comprising sections A, B and C, insulated from each other by the usual insulated joints 99, and signalled for the passage of traffic in an east bound direction. A signal S¹ constructed according to the present invention is located at the exit end of track section A and entrance end of track section B. Also a similar signal S² is located at the exit end of track section B and entrance end of track section C. Associated with the track section A, B and C are the usual track relays and track batteries, of which a track relay T¹ is shown as connected to the entrance end of the track section B and energized from a track battery TB² located at the exit end of track section B, while a track relay T² is shown connected to the entrance end of track section C and controlled by suitable track battery T³ (not shown). A track battery TB¹ is shown as a supply of energy for the exit end of track section A.

Associated with each of the signals S¹ and S² is a battery 100 and 101 respectively for energizing the polarizing electro-magnet of each signal. It is of course to be understood that these batteries 100 and 101 may be replaced by other batteries or sources of energy at the signal location such as batteries TB¹ and TB² respectively.

Pole changing contacts 102 and 103 are operated by the neutral armature of the signal S¹ which is represented by a dotted line, and similarly contacts 104 and 105 are operated by the neutral armature of the signal S².

The track relays T¹ and T² are of the polar neutral type having neutral contacts 106 and 107 respectively which assume energized positions each time the relay is energized. The relay T¹ has polar contacts 108 and 109 while the relay T² has polar contacts 110 and 111. These polar contacts assume right hand positions as shown when

positive potential is applied to the left hand terminals; and assume left hand dotted line positions when negative potential is applied.

Let us assume that a train is passing in an east bound direction from track section A to track section B. The entrance of a train upon track section B deenergizes the track relay T¹ so that the circuit energizing the operating electromagnet of signal S¹ is opened at a front contact 106. The deenergization of the neutral armature of the signal S¹ causes the contacts 102 and 103 to assume deenergized positions, in which positions the polarity of the current supplied to the track section A is reversed. Also, with the operating electro-magnet of the signal S¹ deenergized, the said signal displays its most restrictive indication, such as red.

The passage of this train from track section B into track section C causes the deenergization of the track relay T² which similarly causes the de-energization of the operating electro-magnet of signal S² by the opening of its circuit at front contact 107. This causes the contacts 104 and 105 operated by the neutral armature of signal S² to assume deenergized positions, in which 25 positions the polarity of the current applied to the track section B is reversed, which reverses the polar contacts 108 and 109 of the track relay T¹ to left-hand dotted line positions.

With negative potential applied to the left hand terminal of the track relay T¹, the neutral contact 106 is in an energized position and the polar contacts 108 and 109 are in left hand dotted line positions, thus energizing the operating windings of the signal S¹ with reverse polarity. This energization of signal S¹ energizes the contacts 102 and 103 which apply potential to the track section A of the normal polarity. Thus, the signal in the rear of signal S¹ displays a least restrictive indication, such as green, while the signal S¹ displays an indication of intermediate restriction, such as yellow.

The signal S² is of course displaying its most restrictive indication, such as red. However, when the train passes beyond the track section C, the track relay T² will be energized with reversed polarity, in a similar manner as the track relay T¹ is energized with reverse polarity when a train is in track section C. Also, with the train beyond the track section C, the signal S² will display an indication of intermediate restrictiveness which energizes the contacts 104 and 105 to place normal polarity upon the track section B. This energizes the track relay T¹ in the normal manner, as shown, so that the operating electro-magnet of the signal S¹ is energized with normal polarity so that it displays its least restrictive indication. Further operation is merely a repetition of the functions heretofore described.

More specifically, the track relay T¹ is energized from the track battery TB² through a circuit traced as follows:—from the positive terminal of battery TB², through wires 112, 113, 114 and 115, front contact 104, wire 116, the right hand rail of track section B, wire 117, winding 65 of relay T¹, wire 118, left hand rail of track section B, wire 119, front contact 105, wires 120, 121 and 122, to the negative terminal of track battery TB². This circuit places positive potential on the left hand terminal of track relay T¹, which actuates the neutral contact 106 to an energized position and the polar contacts 108 and 109 to right hand positions, as shown.

With the contacts of the track relay T¹ in the positions shown, a normal energizing circuit for 75

the signal S^1 is completed traceable as follows:— from the positive terminal of battery TB^1 , through wires 123 and 124, polar contact 109 in a right hand position, wire 125, operating electro-magnet 5 of signal S^1 , wire 126, front contact 106, wire 127, polar contact 108 in a right hand position, wires 128, 129 and 130, to the negative terminal of track battery TB^1 .

Deenergization, or shunting, of either the track relay T^1 or T^2 opens the energizing circuit at the respective neutral contacts of the relays for the operating electro-magnet of the associated signal S^1 or S^2 respectively, which causes the contacts controlled by the neutral armatures of the respective signals to assume deenergized positions. Assuming the signal S^2 to be deenergized, the contacts 104 and 105 are in deenergized positions which close the reverse energizing circuit for the track relay T^1 . That is, the polarity applied to the track relay T^1 is reversed, so that the positive potential on wire 114 is placed on wire 119 through back contact 105, while the negative potential on wire 120 is placed on wire 116 through back contact 104. This condition causes the polar contacts of track relay T^1 to assume reverse positions, so that positive potential is applied to wire 126 and negative potential is applied to wire 125 as is obvious from the drawings.

30 All other pertinent circuits may be traced by analogy to those as above explained in detail.

A polar-neutral color light signal has been shown and described as giving a plurality of distinctive indications, the control of which is accomplished by polarized energizing circuits. Also, 35 a typical example of circuits, in which it is possible to use such a signal, has been shown and described.

It is obvious from the preceding description 40 that various modifications can be made to the present invention without departing therefrom, such for example, as the various combinations of contacts may be altered to obtain the desired circuits, the combination of contact materials 45 may be changed from carbon to silver, or vice versa, or other similar materials may be used, etc. It might be further noted, that the motor mechanism of the signal can be altered to include permanent magnets in place of the polarizing 50 electro-magnet, and still give the same functional operation of the signal. The specific embodiment is shown as including an electro-magnet because the desired degree of polarization is more easily obtained with an electro-magnet for the current flowing therein may be readily controlled.

Having described one specific embodiment of

a polar-neutral color light signal in accordance with the present invention, it is to be understood that all alterations, modifications and adaptations which may be applied to the present invention to meet the requirements of practical applications, are to be included within the spirit and scope of the invention as set forth in the appended claims.

Having described my invention, I now claim:—

1. In a color light signal, in combination, a 10 neutral armature, a polar armature, coils for operating the armatures, a spectacle, a plurality of screens of varying restrictiveness in the spectacle, a pivot on the spectacle, a connection between the pivot and the neutral armature whereby operation of the neutral armature moves the pivot, a slot frame, a pivot at one end of the slot and carrying the frame, a pin on the spectacle received in, and slidably in, the slot of the frame, a connection between the frame and the polar armature whereby operation of the polar armature rocks the frame on its pivot, the spectacle being biased to give its most restrictive indication with its pin in the frame slot and at the frame pivot when the coils are de-energized, energization of the coils causing the neutral armature to move the spectacle pin along the frame slot and away from the frame pivot, to move the less restrictive screens toward indicating position.

2. In a color light signal, in combination, a 30 neutral armature, a polar armature coils for operating the armatures, a spectacle, a plurality of screens of varying restrictiveness in the spectacle, a pivot on the spectacle, a connection between the pivot and the neutral armature whereby operation of the neutral armature moves the pivot, a slot frame, a pivot at one end of the slot and carrying the frame, a pin on the spectacle received in, and slidably in, the slot of the frame, a connection between the frame and the polar armature whereby operation of the polar armature rocks the frame on its pivot, the spectacle being biased to give its most restrictive indication with its pin in the frame slot and at the frame pivot when the coils are de-energized, energization of the coils causing the neutral armature to move the spectacle pin along the frame slot and away from the frame pivot, to move the less restrictive screens toward indicating position and causing the polar armature to swing the frame on its pivot and rock the spectacle to selectively bring one or the other of the less restrictive screens into indicating position, dependent upon the polarity of energizing current for the coils.

OSCAR S. FIELD.

55
